CLAIM

The ornamental design for a tent, as shown and described.

DESCRIPTION

FIG. 1 is a right front perspective view of the tent according to the present invention;

FIG. 2 is a front view of the tent according to the present invention;

FIG. 3 is a rear view of the tent thereof;

FIG. 4 is a left side view of the tent thereof;

FIG. 5 is a right side view of the tent thereof;

FIG. 6 is a top of the tent thereof; and,

FIG. 7 is a bottom view of the tent thereof.

The broken lines are for the purpose of illustrating portions of the tent that form no part of the claimed design.
